UNITED STATES PATENT OFFICE.

FRANZ HERKENRATH, OF ZURICH, SWITZERLAND, ASSIGNOR, BY MESNE ASSIGNMENTS, TO METALS COATING COMPANY OF AMERICA, OF BOSTON, MASSACHUSETTS, A CORPORATION OF MASSACHUSETTS.

APPARATUS FOR MELTING AND SPRAYING FUSIBLE SUBSTANCES.

1,151,586.

Specification of Letters Patent. Patented Aug. 31, 1915.

Application filed March 21, 1914. Serial No. 826,137.

To all whom it may concern:

Be it known that I, FRANZ HERKENRATH, a citizen of the German Empire, residing at Zurich VI, in Switzerland, have invented 5 certain new and useful Improvements in Apparatus for Melting and Spraying Fusible Substances, of which the following is a specification.

The object of this invention is to provide 10 improved means for melting and spraying fusible substances, such as metals, for the purpose of coating surfaces therewith.

To this end I use a stream of heated gas, in the path of which I place the fusible substance, the temperature of the gas being 15 sufficiently high to melt the substance. The function of the gas is thus in part analogous to that of the blow pipe flame used in some forms of the so-called "Schoop" process, but 20 the gas also has a propulsive effect on the molten substance, and thus effects the spraying, or assists in that operation. In general I find it more economical to use, in addition to a stream of heated air or other gas, where- 25 by the substance is melted, a blast device acting in conjunction with the said stream of gas.

Four embodiments of apparatus suitable 30 for carrying this improved method into effect are shown in the accompanying drawing, in Figures 1, 2, 3 and 4 respectively, parts of the apparatus in all the views being shown in section.

Referring in the first instance to Fig. 1, *a* 35 designates a coiled tube of electrically conductive but resistant material, and *b* a feed pipe through which a stream of gas is supplied to the tube *a*, so that the gas issues from the tube at *c*. Around the discharge 40 end *c* of the tube *a*, and concentric therewith, is an annular blast nozzle *d*, to which a stream of gas is fed through a pipe *e*. Electric current is fed through the tube *a* by means of wires *w* and heats the said tube 45 sufficiently to raise the gas therein to the temperature required for melting a rod or wire *f* of the fusible substance held in front of the nozzle and fed forward through a guide *g* at the rate required.

50 In the modification shown in Fig. 2 a tube *a*¹ of refractive material incloses an electric resistance *b*¹, through which current is fed by means of wires *w*¹. A stream of

gas is fed into the tube *a*¹ by means of a pipe *b*¹, and passes out through a short pipe *b*², the discharge end of which is surrounded by an annular blast nozzle *d*¹. The stream of gas flowing through the tube *a*¹ is heated by the resistance *b*¹ to the temperature required for melting the fusible substance. 55

In the modification shown in Fig. 3 a tube *a*² of refractive material such as carbon, graphite, carborundum or the like is partly inclosed by a metal tube *b*³, into which a stream of gas is fed through a pipe *b*⁴. The tube *a*², which projects at *c*¹ from the tube *b*³, is electrically insulated from the latter by collars *m*, *n*, and by a holder *k* which embraces the inner end of the tube *a*² and is movable in the tube *b*³, so that the tube *a*² 60 can freely expand. The holder *k* has ducts *d*³ terminating inside the holder at orifices in the wall of the tube *a*², so that the stream of gas fed through the pipe *b*⁴ into the interior *r* of the tube *b*³ passes through the 65 ducts *d*³ into the tube *a*² and is discharged from the latter outside the tube *b*³. The outer end *c*¹ of the tube *a*² is surrounded by an annular blast nozzle *d*². Electric current 70 is fed through the tube *a*² by means of wires *w*² and connections *w*⁴, so that the tube becomes hot and heats the gas passing therethrough to the required temperature. A 75 temperature of 2000° C. can easily be attained with this arrangement, and gas can be fed through the tube *a*² at high pressure 80 without risk of bursting the same, as the pressure outside the said tube is equal to that inside. 85

In the modification shown in Fig. 4 a tube *a*³ of fire-clay or other refractive material is filled with a granular heat conducting mass *b*⁵, for example with particles of carbon, the interstices of which are adequate to give passage to a stream of gas fed into the tube 90 through a pipe *b*⁶ and discharged through a nozzle *a*⁴ arranged in proximity to a guide *g*¹, through which a wire *f*¹ of the substance to be melted and sprayed is fed. The tube *a*³ and the granular carbon therein are heated by a burner *t*. Combustible or non-combustible gas may be used, and acquires reducing properties by contact with the carbon in the tube *a*³. 95

With the appliances shown in Figs. 1, 2 100 and 3, I preferably use gases of a chemically

neutral or reducing quality in order to prevent oxidation of the electric conductors and of the substance melted.

What I claim as my invention and desire 5 to secure by Letters Patent of the United States is:—

1. An apparatus for producing a hot gas-blast for melting and spraying fusible substances which comprises a gas-conduit having 10 a discharge orifice, means to heat said conduit above the melting point of said fusible substance, a gas-holding member partly surrounding said conduit, the discharge orifice of said conduit being outside said gas-holding member, and means for supplying gas 15 under pressure to said conduit and said gas-holding member.

2. An apparatus for producing a hot gas-blast for melting and spraying fusible substances, which comprises a gas-conduit having 20 a discharge orifice, means to heat said conduit above the melting point of said fusible substance, a tube closed at both ends partly surrounding said conduit, the discharge 25 orifice of said conduit being outside said tube, and means for supplying gas under pressure to said conduit and tube.

3. An apparatus for producing a hot gas-blast for melting and spraying fusible substances which comprises a gas-conduit having 30 a discharge orifice, an electric heating device to heat said conduit above the melting point of said fusible substance, a gas-holding member partly surrounding said con-

duit, the discharge orifice of said conduit 35 being outside said gas-holding member, and means for supplying gas under pressure to said conduit and said gas-holding member.

4. An apparatus for producing a hot gas-blast for melting and spraying fusible substances which comprises a gas-conduit having 40 a discharge orifice, an electric heating device to heat said conduit above the melting point of said fusible substance, a tube closed at both ends partly surrounding said 45 conduit, the discharge orifice of said conduit being outside said tube, and means for supplying gas under pressure to said conduit and tube.

5. An apparatus for producing a hot gas-blast for melting and spraying fusible substances which comprises a gas-conduit of 50 electrically conductive material having a discharge orifice, means for feeding an electric current to and from said conduit to heat same, a tube closed at both ends partly surrounding said conduit, the discharge orifice of said conduit being outside said tube, and means for supplying gas under pressure to said conduit and tube. 55

In witness whereof I have signed this specification in the presence of two witnesses.

FRANZ HERKENRATH.
